(57) **CLAIM**

The ornamental design for an embroidery machine, as shown and described.

DESCRIPTION

FIG. 1 is a perspective view of an embroidery machine;
FIG. 2 is a front view thereof;
FIG. 3 is a top view thereof;
FIG. 4 is a right-side view thereof;
FIG. 5 is a rear view thereof;
FIG. 6 is a bottom view thereof;
FIG. 7 is an enlarged cross sectional view thereof, the cross section taken along lines C-C in FIG. 3, and the enlargement defined by lines A-A in FIG. 3 and lines B-B in FIG. 4;
FIG. 8 is an enlarged front view thereof with all broken lines removed;
FIG. 9 is an enlarged left-side view thereof with all broken lines removed; and,
FIG. 10 is an enlarged bottom view thereof with all broken lines removed.
The broken lines depict environmental subject matter only and form no part of the claimed design.
